[57] CLAIM

The ornamental design for an add-on access module for
a telephone set, as shown and described.

DESCRIPTION

FIG. 1 is a front perspective view of the add-on access
module showing my new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a right elevational view thereof;

FIG. 7 is a left elevational view thereof;

FIG. 8 is a front perspective view thereof showing, in
dashed outline, an associated telephone set;

The broken line showing of a fragmentary module sup-
port edge in FIG. 1.

FIG. 1

FIG. 2

FIG. 3

FIG. 4

FIG. 5

FIG. 6

FIG. 7

FIG. 8
